Robert Brouillette

(57) **CLAIM**

The ornamental design for a light fixture, as shown.

DESCRIPTION

FIG. 01 is a front elevation view of the light fixture;
FIG. 02 is a bottom plan view of the light fixture of FIG. 01;
FIG. 03 is a right side elevation view of the light fixture of FIG. 01;
FIG. 04 is a top plan view of the light fixture of FIG. 01; and,
FIG. 05 is a perspective view of the light fixture of FIG. 01.
The broken lines shown on the drawings depict portions of
the light fixture that form no part of the claimed design.

1 Claim, 5 Drawing Sheets
